(57) **CLAIM**

The ornamental design for a vehicle exterior, as shown and described.

DESCRIPTION

FIG. 1 is a front perspective view of a vehicle exterior showing our new design;

FIG. 2 is a rear perspective view thereof;

FIG. 3 is a side elevational view, the opposite side being a mirror image thereof;

FIG. 4 is a front elevational view thereof; and,

FIG. 5 is a rear elevational view thereof.

The broken line showings of the wheels, tires, center marquee, front and rear windshield wipers and the tailpipe are for illustrative purposes only and form no part of the claimed design.
